DESIGN FOR A WRINGER

Robert J. Waterworth, Sidney, Ohio, assignor to
Prima Mfg. Company, Inc., Sidney, Ohio, a cor-
poration of Ohio

Application October 9, 1934, Serial No. 53,533

Term of patent 7 years

To all whom it may concern:

Be it known that I, Robert J. Waterworth, a subject of the Kingdom of Great Britain, residing at Sidney, in the county of Shelby and State of Ohio, have invented a new, original, and ornamental Design for a Wringer, of which the following is a specification, reference being had to the accompanying drawings, forming a part thereof.

In the drawings:

Figure 1 is a side elevation of the wringer showing my new design;

Figure 2 is a top plan view;

Figure 3 is an end elevation;

Figure 4 is a sectional view taken on the line 4—4 of Figure 1.

I claim:

The ornamental design for a wringer, substantially as shown.

ROBERT J. WATERWORTH.
